ROTARY BALANCED VANE PUMP

William T. Stephens, Painesville, Ohio

Application November 2, 1945, Serial No. 626,213

7 Claims. (Cl. 103—136)

1

My invention relates to fluid displacement apparatus such as fluid pumps and motors. The invention concerns particularly pumps of the sliding vane type.

It is an object of my invention to provide improved methods and apparatus for delivering or utilizing fluid under pressure in which high efficiency is attained and the parts of the apparatus may be machined easily.

An object of the invention is to provide a construction having a housing with a circular bore and a rotor with a shaft concentric with the bore. Another object is to provide an adjustable sealing segment in the bore between the outlet and inlet ports.

A further object is to provide easy radial sliding of the vanes.

A further object is to balance the rotor vanes hydraulically and to avoid side thrust or binding of the vanes in the slots of the rotor in which they are carried.

Still another object of the invention is to avoid friction causing heat and wear at the bore and at the outer edges of the vanes.

An object is to move the blades or vanes inward by hydraulic pressure as they pass the sealing segment in the bore.

A more specific object is to employ fluid trapped as the vane approaches the sealing segment to depress the vane. Another object is to limit the radially outward movement of the vane caused by centrifugal force so as to cause the vanes to reach only a position in which the outer edges just contact the surface of the bore.

Another object is to equalize fluid pressure under the vane in the vane carrying channel or slot of the rotor and within the bore outside the rotor. It is also an object to avoid trapping of fluid under the vane in the slot in which it is carried.

Other and further objects, features and advantages of the invention will become apparent as the description proceeds.

In carrying out the invention in accordance with a preferred form thereof, I provide a circular-bore pump housing or shell and a concentric rotor with a concentric axis of rotation. The pump housing is provided with inlet and outlet ports, and a sealing segment is secured in the bore between the ports to fill in the space between the rotor and the bore surface of the housing.

The rotor comprises a circular cylinder of smaller radius than the bore in the housing, the sealing segment being of a thickness corresponding with the difference between the radii of the rotor and the housing bore. A plurality of axially extending slots are cut lengthwise in the rotor to receive vanes adapted to slide in and out radially in the rotor as they pass under the seal-

2

ing segment. Preferably the vanes are of T-shaped cross section and T-slots are provided in the rotor for receiving the vanes. The base or T-portion of the slot is preferably radially thicker than the base or T-portion of the vane so as to provide for radial movement of the vane. Openings are provided in the rotor which lie parallel to the direction of movement of the vanes and each vane is provided with one or more pistons each slideable in one of said openings and having a transverse notch engaging the T-portion or base of the vane. Hydraulic pressure applied to the piston by the fluid trapped between the vane and the sealing segment of the vane approaching the sealing segment forces the vane inward radially so as to avoid friction and heating of the outer edge of the vane and avoiding vibration or shock as the outer edge of the vane tends to contact the sealing segment.

A better understanding of the invention will be afforded by the following detailed description considered in conjunction with the accompanying drawing in which Fig. 1 is a cross sectional view of an embodiment of my invention represented as cut by a broken plane 1—1, indicated in Fig. 2, passing through the axis of rotation of the rotor shaft; Fig. 2 is a view of a cross section of the apparatus of Fig. 1 represented as cut by plane perpendicular to the rotor shaft, and Fig. 3 is a fragmentary enlarged view of a portion of a vane at the approach to the sealing segment.

Like reference characters are utilized throughout the drawing to designate like parts.

For the sake of illustration I have shown and described a sliding vane pump having three radially slideable vanes but it should be understood that my invention is not limited to this specific arrangement. In the pump illustrated

in the drawing the housing comprises a cylinder or shell having a concentric circular bore with end cover plates 13 and 14, and preferably circular plates 15 and 16 for defining the ends of a rotor chamber. Ports 17 and 18 are provided at the surface of the housing bore 12 and a sealing segment 19 is secured or formed in the housing bore 12.

The end plates 13 and 14 are secured to the cylindrical shell 11 by suitable means such as machine screws 21.

There is a rotor 22 comprising a right circular cylinder 23 preferably composed of metal carrying vanes or blades 24, 25 and 26. The cylinder 23 is bored to receive a shaft 27 and keyed thereto. Suitable bearings are provided for rotatably supporting the shaft 27 in the pump housing. For example ball bearings 28 and 29 may be provided. The outer ball race for the bearing 28 is secured between the cover plate 13 and the circular plate 15 and the outer ball race for the bearing 29

3

is secured between the circular plate 16 and the cover plate 14. Suitable openings are provided in the plates 15 and 16 and in the cover 14 for the shaft 27.

Preferably T-slots 31 are milled lengthwise in the rotor cylinder 23 for receiving the vanes 24, 25 and 26. The vanes 24, 25 and 26 preferably each have a T-shaped cross-section with a base or T-portion 32 of less thickness or radial dimension than the base or T-portion 33 of the slot 31 in order to permit the vane to move in and out. Preferably one or more holes 34 are drilled radially in each of the vanes 24, 25 and 26 for equalizing the pressure in the base portion 33 of the vane receiving slot inside the vane with the pressure in the space between the cylinder 23 and the surface of the bore 12, and also for preventing fluid from being trapped under the moving vane. In this manner any side thrust of the vanes against the edges of the slots is minimized and the vanes are allowed to move in and out freely as required.

For each of the rotor vanes one or more pistons preferably in pairs are provided, sliding in holes in the rotor cylinder 23 running parallel to the radii of the corresponding vanes. In the arrangement illustrated pistons 35 and 36 are provided slideable in openings 37 and 38 parallel to the direction of radial movement of the vane 24. Similar pistons 41 and 42 are provided slideable in cylindrical openings 43 and 44 parallel to the direction of radial movement of the vane 26, as well as pistons 45 slideable in openings parallel to the direction of radial movement of the vane 25. In order to prevent the movement of the pistons from causing pulsations in the lines through which the fluid is being pumped, adjacent piston receiving holes of adjacent vanes are arranged to communicate with each other and with the space outside the cylinder 23. Thus the openings 38 and 43 are cut deep enough so as to communicate with each other and with an opening 46 which is cut radially in the cylinder 23 in the portion hereof between the openings 38 and 43. Similar radial openings 41 are arranged between the vanes 24 and 25 and between the vanes 25 and 26. Each of the pistons 35, 36, 41, 42 and 45 is notched on the side to engage the side of the base or key portion 32 of one of the vanes 24, 25 or 26.

The sealing segment 19 is mounted against the surface of the bore 12 of the housing shell 11 between the ports 17 and 18. It is arranged to fit closely against the internal surface of the shell 11 and to make a sliding fit with the outer surface of the cylinder 23, tight enough to seal the joint against fluid leakage. Means such as flat headed bolt 48 are provided for securing the sealing segment 19 in position. For simplicity in the drawing only one bolt 48 is shown but it will be understood that the member is not limited to the use of only one such bolt. Preferably the sealing segment 19 is composed of spring steel and of such shape that it tends to spring inward further than the surface of the cylinder 23 so that by tightening the nut 49 on the bolt 48, the position of the inner surface of the sealing segment 19 may be properly adjusted for making a close seal with the outer surface of the cylinder 23. The outer surface of the segment 19 is flattened sufficiently to provide a space 51 permitting such adjustment. A portion of the inner surface of the sealing segment 19 is cylindrical to conform substantially to the shape of the outer surface of the rotor cylinder 23. The remainder

4

of the inner surface is curved so as to form two gradual transition curves 52 and 53 providing transitions from the radius of the bore 12 of the housing shell 11 to the radius of the rotor cylinder 23 and vice versa.

The pump illustrated is adapted to pump fluid such as oil or the like for a fluid pressure system in either direction by reversing the direction of rotation of the rotor 22, however for the sake of simplicity it will be assumed in the explanation of the operation that the rotor 22 is rotated in the counter clockwise direction, in which case the port 17 becomes the inlet port and the port 18 becomes the outlet port and the fluid pumped is caused to travel in the direction of the arrows 54 through tubing 55 and 56 communicating with the inlet and outlet ports 17 and 18 respectively.

The outermost surfaces of the crosswise or T-portions 33 of the slots 31 for the vanes are in such position that the vanes are prevented from pushing against the bore 12 of the housing 11 with sufficient force to cause serious friction but are permitted to contact the surface of the bore 12. It should be understood that the dimensions 20 may be such that initially the outer edges of the vanes tend to rub with excess pressure against the bore surface owing to centrifugal force but as the vanes wear in only sufficient contact remains to seal the space between the rotor cylinder 23 and the surface of the bore 12. Consequently 25 the space between adjacent vanes is enclosed. As the rotor rotates, fluid is drawn into the port 17 and swept circumferentially around the inner surface of the bore so as to be expelled through 30 the port 18. The outer surface of the cylinder 23 is sealed at the sealing segment 19 so as to prevent fluid from being carried around from the outlet port 18 back to the inlet port 17. With 35 the rotor in the position illustrated the outer edge of the vane 24 has already traveled part way along the transition curve 52 of the sealing segment 19. It will be apparent that as soon as the forward edge 57 of the vane 24 has reached the forward corner 58 of the outlet port 18, some fluid 40 is trapped in the space between the vane 24 and the sealing segment 19. This space becomes continually smaller as the rotor rotates, being reduced to the volume presented at 59 in Fig. 3 when the rotor reaches the angular position illustrated. 45 In consequence fluid enters bore 37 in the space 61 above piston 35 and inward pressure is exerted against the outer end surface of the piston 35 causing the vane 24 to be forced inward sufficiently to relieve the friction between the corner 51 of the vane 24 and the transition curved 50 surface 52 of the sealing segment 19. A slight flow of the trapped fluid takes place around the leading edge 51 of the vane 24, so as to provide lubrication and cooling. In this manner the 55 vanes are depressed by hydraulic pressure so as to pass the sealing segment 19. This action avoids the shock of the vane striking this segment and also avoiding the friction, heating, and wear which would be caused if a mechanical contact between 60 the vane 24 and the sealing segment 19 were depended upon for depressing the vane 24. With the rotor 23 rotating in the opposite direction, the same function of depressing the vane 24 would be performed by the piston 36. It will be recalled 65 that piston 35 and 36 are arranged to engage the vanes 24 by reason of the notches therein. 70

The ports 18 and 17 lie between the plates 15 and 16. Suitable packing means are provided to prevent axial leakage of the fluid being pumped. The circular plates 15 and 16 may be

provided with conventional O-ring seals 62. The shaft 27 may be packed by means of a felt packing ring 63 clamped to a ring 64 riding against a bushing 65 in the shaft opening of the cover plate 14. A bent metal clamp 66 is provided for securing the felt 63 against the ring 64, and a spring 67 is provided for holding the ring against the bushing 65. A suitable means such as split spring rings or the like, 68 are provided for holding the inner ball races on the shaft 27. A chamfered ring 69 is provided for holding the inner edge of the felt packing ring 63 which preferably is secured to the shaft 27 by a band 70.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim is:

1. A sliding vane pump comprising in combination a housing having a right circular cylindrical bore with inlet and outlet openings and a sealing segment therebetween, a rotor having a shaft concentric with said bore, a plurality of radially movable hydraulically balanced vanes in said rotor and hydraulic means for pressing the vanes radially inward to avoid friction at the sealing segment between inlet and outlet openings of the housing.

2. A sliding vane pump comprising in combination a housing having a circular cross section bore therein, a rotor mounted in said housing having axially extending T-slots therein and vanes with T-shaped cross-section mounted in said T-slots, the outer edges of said T-slots being set in such position with respect to the dimensions of the vanes that the outer edge of the cross bar of the vanes engages the outer edge of the T-slots and the outer edges of the vanes just come in contact with the bore surface thereby avoiding excess friction between the vanes and the bore.

3. A sliding vane pump comprising in combination a housing having a bore therein with inlet and outlet ports, a rotor mounted coaxially rotatable in said bore having radially movable vanes adapted to contact the surfaces of said bore, a sealing segment in said bore and disposed between the inlet and outlet ports of the housing and engaging the periphery of said rotor, said rotor having pistons therein connected to said vanes whereby a vane approaching said sealing segment produces a pressure acting upon an associated piston to depress said piston and said vane thereby avoiding friction between the vane and said sealing segment.

4. A sliding vane pump comprising in combination a housing having a bore therein with inlet and outlet ports, a rotor rotatably mounted in said bore having radially movable vanes adapted to contact the surfaces of said bore, means for hydraulically balancing the vanes, means for preventing said vanes from sweeping fluid back from the outlet port to the inlet port as the vanes rotate with said rotor, and means for generating hydraulic pressure as each vane approaches the inlet port after it leaves the outlet port in order to depress the vane sufficiently to minimize frictional contact of the vane with the

means for preventing fluid from being swept from the outlet port to the inlet port.

5. A sliding vane pump comprising in combination a housing with inlet and outlet ports and a movable member carrying vanes adapted to sweep fluid from the inlet port to the outlet port and a sealing segment between the outlet port and inlet port for preventing fluid from being returned from the outlet port to the inlet port, the sealing segment being so mounted as to trap fluid between the outlet port and the sealing segment as the vane approaches said sealing segment and means responsive to trapped pressure for depressing the vane to minimize frictional contact with said sealing segment.

6. A sliding vane pump comprising in combination a housing having a circular-cross-section bore therein with inlet and outlet ports, a rotor of substantially circular-cross-section mounted in said bore rotatable about an axis concentric with said bore, said rotor having a smaller radius than said bore, and a sealing segment mounted in said housing having a thickness substantially equal to the difference in radius between said bore and said rotor whereby leakage of fluid from the outlet port to the inlet port of the bore is arrested, wherein the sealing segment is composed of material having permanent set in a shape with an outer surface of different radius from the bore of said housing and an inner surface normally such as to have a radius less than the rotor surface and means whereby said segment is sprung so as to increase the internal radius to the radius of the rotor.

7. A sliding vane pump comprising a housing having a cylindrical bore therein with inlet and outlet ports, a rotor of smaller cross-section than said bore and rotatably mounted therein, a sealing segment of spring material mounted in said bore and disposed between said ports, said sealing segment having inner and outer generally parallel faces joined by tapered edge portions, said inner and outer surfaces being normally of a radius slightly greater than that of said rotor and said housing bore respectively, means to adjustably fasten said sealing segment in said bore and disposed substantially midway between the tapered edges of said sealing segment, said edges of said segment normally engaging the wall of said bore with the remainder of the outer surface of said segment spaced from said bore, whereby the radius of curvature of said inner segment face may be adjusted to substantially equal that of said rotor, and a plurality of pumping vanes slidably mounted in the rotor and formed to slide across the sealing segment.
